CONTROL SYSTEM

Willard A. Derr, Wilkinsburg, Pa., assignor to
Westinghouse Electric Corporation, East Pittsburgh, Pa., a corporation of Pennsylvania

Application July 18, 1944, Serial No. 545,511

7 Claims. (Cl. 171—118)

My invention relates, generally, to control systems and has reference, in particular, to electrical synchronizing control systems.

Generally stated, it is an object of my invention to provide a synchronizing control system that is simple and inexpensive to manufacture and is easy to operate.

More specifically, it is an object of my invention to provide for synchronizing two or more alternating-current sources on a common bus when there is no bus potential transformer available.

It is also an object of my invention to provide, in a simple and effective manner, for converting manual switching stations to supervisory control where there is no bus potential transformer available.

Another object of my invention is to provide for selectively connecting a synchronizing device to two or more sources of alternating current which are to be synchronized on a common bus.

Yet another object of my invention is to provide for automatically determining whether a common bus to which two or more sources of alternating current may be connected is already energized and, at the same time, provide a synchronizing control potential from one or another of the sources from which it is energized.

Other objects will in part be obvious, and will in part be described hereinafter.

In practicing my invention, synchronizing potential circuits are provided to each of several alternating sources which it may be desired to synchronize on a common bus. Voltage responsive relays associated with each circuit automatically interconnect the circuits so as to provide a synchronizing control potential from one or another of the sources which may be connected to the bus. A control switch associated with each source is operated when it is desired to synchronize a particular source with the common bus, to apply to a synchronizing device, a potential from the source and a control potential from one or another of the sources already connected to the common bus, in order to give the operator an indication of when the particular source is synchronized with the bus.

For a more complete understanding of the nature and scope of my invention, reference may be made to the following detailed description which may be read in connection with the accompanying drawings, in which:

Figure 1 is a diagrammatic view of a manual control system embodying the invention in one of its forms; and

Fig. 2 is a diagrammatic view of a supervisory

control system embodying the invention in another of its forms.

Referring to Fig. 1, the reference numeral 100 may denote, generally, a control system for synchronizing a plurality of alternating-current sources such as, for example, the generators 101, 102 and 103 with a common bus 105. As is often the case with relatively small manually-controlled switching stations, potential transformers 106, 107 and 108 may be provided in connection with the generators 101, 102 and 103, respectively, but the bus 105 may be without a bus potential transformer. Connection of the generators 101 through 103 to the bus 105 may be effected in any well-known manner, such as by circuit breakers 110, 111, and 112 having operating windings 113, 114 and 115 energizable under the control of suitable switch means represented by the push-button switches 117, 118 and 119, respectively.

20 In order to provide for synchronizing each of the generators with the common bus, synchronizing means such as the synchroscope 120 may be utilized, having a synchronizing switch 122 associated therewith for effecting connection thereof to potentials from the sources to be synchronized.

For the purpose of providing the necessary synchronizing potentials, control means such as the relays 124, 125 and 126 may be provided in conjunction with suitable control switches 127, 128 and 129 for energizing the operating windings 131, 132 and 133 thereof. The control means may be operable to connect to the synchroscope 120 a synchronizing potential from the potential transformer of the source to be synchronized, and at the same time apply to the synchroscope a synchronizing control potential from a potential transformer of one of the other sources, depending upon which of the other sources may be connected to the bus. This connection may be effected by providing each of the sources with a selective control relay such as, for example, the voltage-responsive control relays 135, 136 and 137, respectively. The control relays 135, 136 and 137 may be provided with operating windings 139, 140 and 141 connected to corresponding phases of the sources 101, 102 and 103 through the potential transformers 106, 107 and 108, respectively.

50 The selective connection of the synchronizing potential from one or another of the sources connected to the bus may be effected by using normally open and normally closed contact members of the control relays for selecting which of the other sources is to be connected to the syn-

chronizing device. Normally open contact members may be provided, in conjunction with each of the circuit breakers, for preventing the application of a synchronizing control voltage to the synchronizing device when the generator associated therewith is operating but is disconnected from the bus by reason of its circuit breaker being open.

With the system in the de-energized position as shown, any one of the circuit breakers may be closed to connect its associated generator to the bus 105 which is not energized, since the synchroscope remaining stationary with the source to be synchronized being brought up to frequency indicates that the bus is deenergized. Should the circuit breaker 112 be closed to connect the generator 103 to the bus 105, after the generator has been brought up to speed, the control relay 137 will be already in the energized position, since its operating winding 141 is connected directly across the secondary winding of the potential transformer 108. Accordingly, normally open contact members 137a and 137c will be closed, while normally closed contact members 137b and 137d will be open. Since normally open contact members 112a of the circuit breaker 112 are closed, a synchronizing control potential may be made available at the control switches 124 through 126 from the potential transformer 108.

To synchronize the generator 102 with the common bus 105 the switch 128 may be closed to energize the operating winding 132 of the control switch 125, and the synchronizing switch 122 may be operated to the synchronizing position. A synchronizing potential is thereby applied from the generator 102, which is to be synchronized, from the potential transformer 107, through conductors 144 and 145, contact members 125a and 125b, and conductors 147 and 148, through the synchronizing switch 122 to the synchroscope 120. At the same time, a synchronizing control potential is automatically applied from the generator 103, which is connected to the common bus 105 from the potential transformer 108, through conductor 150, contact members 135b, conductor 151, contact members 125c and conductor 153, through the synchronizing switch 122 to the synchroscope 120. The other terminal of the potential transformer 108 is connected to the synchroscope through conductor 155, contact members 112a, conductor 156, contact members 135d, conductor 157, contact members 125d, conductor 158 and through the synchronizing switch 122. As soon as the synchroscope 120 indicates synchronism, the push-button switch 118 may be closed to effect operation of the circuit breaker 111 to connect the generator 102 to the bus.

In a like manner, should it be desired to synchronize the generator 101 with the bus 105, the switch 127 may be closed to operate the control switch 124, and the synchronizing switch 122 may be actuated to the operating position. Since both of the control relays 136 and 137 are in the energized position, the synchronizing control potential will be supplied from the potential transformer 108, the same as if only the generator 103 were connected to the common bus. Should the generator 103 be disconnected and only the generator 102 be connected to the bus, the control relay 137 would be in the de-energized position, while the control relay 136 would be in the energized position. Accordingly, the synchronizing control potential would be supplied by the generator 102 from the potential transformer 107, through contact members 136a of the control re-

lay 136. The synchronizing potential from the generator 101 is, of course, supplied by the potential transformer 106 over an obvious circuit through contact members 124a and 124b of the control switch 124. It will thus be seen that a synchronizing control potential is automatically made available under the control of the control relays for synchronizing any one of the generators with the common bus, whenever one or more of the other generators may be already connected to the bus.

Referring to Fig. 2, the reference numeral 160 may denote, generally, a synchronizing control system for a plurality of circuit breakers 110, 111 and 112, which may be located at a remote station 11 and disposed to be operated from a control station 10 by means of suitable supervisory control equipment over a single control circuit or channel 12. The supervisory control equipment may be of any suitable character and may, for example, be similar to that shown and described in detail in Patent No. 1,994,908, which issued on March 19, 1935, to Gennero De Croce, and is assigned to the assignee of the present invention. Since the system of the De Croce patent is being used as illustrative of one form of supervisory control equipment with which the present invention may be combined, and the present invention is not concerned with the particular details of all portions thereof, the greater portion of the control station and remote station control and supervisory equipment has been shown boxed. Such of the equipment as has been modified to co-operate with applicant's control system has been shown in detail. The same reference characters have been used to designate elements shown in the original system of the aforesaid patent and different reference characters have been used to designate apparatus not shown in the patent.

As will be clearly seen from the drawings, the control relays 135, 136 and 137 may be used in exactly the same manner as described hereinbefore in connection with the system of Fig. 1, for selectively determining which of the potential transformers 106, 107 or 108 shall provide the synchronizing control potential. In this respect, while the common bus 105 and the connections from the individual sources have been shown as single-phase instead of three-phase as in Fig. 1, it will be understood that this change is merely for the purpose of simplification, so as to reduce the number of conductors and contact members, and in no manner affects the invention. The control switches 124, 125 and 126 are likewise used in an identical manner to select the synchronizing potentials thereby applied to the synchronizing device.

Instead of effecting manual operation of the control switches 124, 125 and 126, as in the system of Fig. 1, operation of the control switches in Fig. 2 may be selectively effected over the channel 12 by means of control switches 53a, 53b and 53c, corresponding to the switch 53 at the control station of the system in the aforesaid patent. Control means, such as the line relays 43a, 43b and 43c, corresponding to the line relay 43 of the system of the patent, may be used at the remote station in a similar manner to the line relay 43 of the system of the patent for both connecting the synchronizing equipment 15 to the synchronizing indicating instrument 49 at the control station and effecting energization of the operating winding of the particular con-

trol switch associated with the source it is desired to synchronize with the common bus.

With the system in the de-energized position, as shown, any one of the circuit breakers 110, 111, or 112 may be readily closed merely by energizing the respective closing circuit through conductors 82a, 82b or 82c through closing the corresponding one of the control switches 66a, 66b or 66c at the control station, which corresponds to the control switch 66 of the De Croce system, since with the bus de-energized the indicating device 40 would merely give a half-scale reading indicating a de-energized bus. Should the control switch 66c be closed, a predetermined frequency is transmitted over the channel 12 for effecting operation of the circuit breaker 112 to the closed position in a manner similar to that described in the De Croce patent. The control relay 137 is thereupon energized, since it is connected directly across the primary winding of the potential transformer 108.

Should it then be desired to close the circuit breaker 111, the control switch 53b may be closed to effect operation of the line relay 43b. The synchronizing device 15 is thereby connected to the indicator 40 at the control station, and the operating winding 132 of the control switch 125 is energized over an obvious circuit through contact members of the line relay 43b. Accordingly, a synchronizing potential is applied to the primary windings 36 and 24 of the synchronizing transformers from the potential transformer 107 through contact members 125a and 125b of the control switch 125. At the same time, a synchronizing control potential is applied to the primary windings 23 and 38 of the synchronizing transformers through contact members 125c and 125d, normally closed contact members 135b and 135d and normally closed contact member 112a from the potential transformer 108. Accordingly, when the voltages from the potential transformers 107 and 108 are both in phase and of equal magnitude, the direct current potential applied to the indicating means 40 by the rectifiers 16, 17 and 18 of the synchronizing equipment 15 will be at a minimum indicating synchronism. The circuit breaker control switch 66b at the control station may then be closed to effect closure of the circuit breaker 111.

Likewise, when it is desired to close the circuit breaker 110, the control switch 53a at the control station may be closed to secure indication of synchronism. The synchronizing potential will be supplied from the potential transformer 106, while the synchronizing control potential, which is representative of the potential on the common bus 105, will be supplied from the potential transformer 108 when both of the circuit breakers 111 and 112 are closed by reason of the circuits provided by the control relays 136 and 137. Should only the circuit breaker 111 or 112 be closed, the synchronizing control potential will, of course, be provided from the potential transformer 107 or 108, respectively.

Indication of the operating positions of the circuit breakers may be obtained by means of the indicating circuits established through conductors 86a, 86b and 86c in the manner described in the De Croce patent. Trip circuits for the circuit breakers may be provided also in the same manner described in the De Croce patent over conductors 87a, 87b and 87c.

From the above description and the accompanying drawings, it will be apparent that I have provided, in a simple and effective manner, for

synchronizing a plurality of alternating-current sources with a common bus which does not have a bus potential transformer for supplying a synchronizing control potential. The synchronizing control potential is automatically supplied through control circuits provided by the voltage responsive relays and the control switches from one or another of the sources which may be already connected to the common bus. Such a control system makes it possible to apply supervisory control to existing manual switches which do not have a bus potential transformer, and also provides a simple and effective synchronizing system for manual switching stations which are without a bus potential transformer.

Since certain changes may be made in the above-described construction and different embodiments of the invention may be made without departing from the spirit and scope thereof, it is intended that all the matter shown in the above description and in the accompanying drawings shall be interpreted as illustrative and not in a limiting sense.

I claim as my invention:

1. A synchronizing system for a plurality of alternating-current sources disposed to be connected to a bus comprising, a synchronizing device, switch means operable to apply a synchronizing voltage to the synchronizing device from a source which is to be synchronized with the bus, and means responsive to the energization of the bus from any of the other sources for applying a synchronizing voltage from one of said sources to the synchronizing device independently of the bus.

2. A synchronizing system for three or more alternating-current sources disposed to be synchronized on a bus without a bus potential transformer comprising, a synchronizing indicator, switch means associated with each source for applying voltages to the synchronizing indicator from the source to be synchronized and from a source connected to the bus, and means responsive to the voltage of each source operable to selectively determine which of the other sources applies the voltage to the synchronizing indicator.

3. A synchronizing system for a plurality of sources having potential transformers and disposed to be synchronized on a bus not having a potential transformer comprising, a synchronizing device, circuit means including a switch associated with each source operable when the source is to be synchronized to apply control voltages from the potential transformer associated with said source and from one of the other potential transformers to the synchronizing device, and means including control means responsive to the energization of the bus from one or more of said other sources and means responsive to the connection of one of the other sources to the bus for selectively determining which of the other sources shall supply the control voltage.

4. For use in synchronizing any one of three or more alternating-current sources each having a potential transformer on a common bus without means for obtaining a bus a potential, a synchronizing device, means including a switch associated with each source operable to connect the synchronizing device to the potential transformer of a source which is to be synchronized with the bus, and means including relay means responsive to the voltage of each source and to the connection thereof to the bus effective to selectively connect the synchronizing device to the

potential transformer of one of the sources connected to the common bus.

5. A synchronizing system for a plurality of alternating-current sources having individual potential transformers and switch means for connecting them to a common bus comprising, a synchronizing indicator, synchronizing switch means associated with each of the sources independently operable to connect the synchronizing indicator to the one source associated therewith, means associated with each source including a relay responsive to the voltage of its associated source for selectively connecting the synchronizing indicator to one of the other sources, and circuit means including means responsive to the position of the switch means for selectively effecting connection of one or the other of the other sources to the synchronizing device when another of the sources is being synchronized.

6. For use in synchronizing at a remote station a plurality of alternating-current circuits on a common bus, a synchronizing indicator located at a control station, a synchronizing device located at the remote station, switch means associated with each one of the circuits for applying a synchronizing potential from said circuit to the synchronizing device for synchronizing said one circuit, means responsive to the energization of the common bus by another of the circuits for selectively applying a synchronizing potential to the synchronizing device from said other circuit independently of the bus, and supervisory control

means including a plurality of control switches at the control station and supervisory control apparatus at the control and remote stations operable to selectively operate the switch means and transmit a synchronism indication from the synchronizing device for operating the synchronizing indicator.

7. A supervisory control system for a plurality of circuit breakers at a remote station each operable to connect an alternating-current circuit to a common bus which is not provided with means for obtaining a synchronizing potential, comprising, a synchronizing transmitter, control means associated with each circuit breaker selectively operable to apply a synchronizing voltage from the associated circuit to the synchronizing transmitter, means associated with each circuit responsive to the energization of the bus from one of the other circuits and co-operative with the control means to selectively connect the synchronizing transmitter to one of the other circuits for obtaining a reference voltage independently of the bus, a synchronizing indicator at a control station, supervisory control apparatus at the remote and control stations for effecting operation of the control means from the control station to cause the synchronizing indicator to operate under the control of the synchronizing transmitter and permit selectively synchronizing the circuits to the bus.

WILLARD A. DERR.
